(57) **CLAIM**

The ornamental design for a confectionery piece, as shown and described.

DESCRIPTION

FIG. 1 is a top perspective view of a confectionery piece showing our new design;

FIG. 2 is a top plan view of FIG. 1;

FIG. 3 is a right side elevation view of FIG. 1;

FIG. 4 is a left side elevation view of FIG. 1;

FIG. 5 is a top side elevation view of FIG. 1; and,

FIG. 6 is a bottom side view of FIG. 1.

The broken lines in FIGS. 1-6 illustrate portions of the confectionery piece that form no part of the claimed design.
